CLAIM

The ornamental design for a pavement breaker, as shown and described.

DESCRIPTION

FIG. 1 is a right/front perspective view of the pavement breaker.

FIG. 2 is a left side view thereof.

FIG. 3 is a right side view thereof.

FIG. 4 is a top view thereof.

FIG. 5 is a bottom view thereof.

FIG. 6 is a front view thereof; and,

FIG. 7 is a rear view thereof.

The broken line showing of elements of the pavement breaker form no part of the claimed design.
